UNITED STATES PATENT OFFICE.

HENRY J. SMITH, OF PITTSBURG, PENNSYLVANIA, ASSIGNOR TO BRYCE,
WALKER & CO., OF SAME PLACE.

DESIGN FOR A CREAM-PITCHER.

SPECIFICATION forming part of Design No. 12,189, dated March 15, 1881.

Application filed January 26, 1881. Term of patent 7 years.

To all whom it may concern:

Be it known that I, HENRY J. SMITH, a citizen of the United States, residing at Pittsburgh, in the county of Allegheny and State of Pennsylvania, have invented and produced a new and original Design for Cream-Pitchers, of which the following is a specification, reference being had to the accompanying drawings, forming part thereof.

10 Figure 1 is a side elevation of my newly-designed cream-pitcher, which presents the same appearance from the opposite point of view. Fig. 2 is an elevation, in perspective, of the same.

15 The leading feature of my design consists in the upward and outward curvature of the two pouring-lips in opposite directions from the top of the vase or main body of the pitcher, and the arrangement of the two handles 20 on opposite sides of the pitcher and under the curves of the lips, thus giving the article a symmetrical and balanced effect to the eye.

25 A subsidiary feature of my design consists in a bead surrounding the top of the vase or main body of the pitcher and forming a base from which the curved lips spring upward and outward in opposite directions, while their curved edges terminate in narrow webs springing from said bead and having corrugated 30 upper edges, which join with the edges of the lips in continuous outline.

35 The design also consists in the handles, each formed of two rings joined edgewise, one below the other, and projecting from the vase or main body of the pitcher directly under the curves of the lips.

40 The separate features, while being ornamental and of pleasing appearance in themselves, combine to form a unitary effect of symmetry and graceful poise.

45 The letter A designates the vase or main body of the pitcher; B, the bead at its top; C C, the upwardly and outwardly curved lips springing in opposite directions from this bead; and D D are the narrow webs connecting the lips and having the corrugated upper edge, which joins the edges of the lips in continuous outline.

E E are the handles, projecting from opposite sides of the vase or main body of the 50 pitcher directly under the curves of the lips, each of these handles being composed of two rings, one below and joined to the other.

The relative arrangement of the various features produces a neat, symmetrical, and highly 55 ornamental ensemble.

I claim—

1. The design for a cream-pitcher, consisting in the vase or main body A, having the two upwardly and outwardly curved lips C C, 60 projecting from opposite sides of its top, and the two handles projecting from said vase directly under the curves of the lips.

2. The design for a cream-pitcher, consisting in the vase having the bead B at its top 65 and forming a base from which the lips C C spring upwardly and outwardly, and the narrow webs D D, having the corrugated edges, which join with the edges of the lips in continuous outline.

3. The design for a cream-pitcher, consisting of the vase or main body A, having the two lips C C curving upwardly and outwardly from opposite sides of its top, and the two handles E E, projecting from the vase directly 75 under the curves of the lips, and each composed of two rings joined edge to edge, one below the other.

4. The design for a cream-pitcher, consisting in the vase or main body A, the bead B, surrounding its top, the two lips C C, curving upwardly and outwardly in opposite directions from said bead, the narrow webs D D, connecting the lips and having the corrugated upper edges, which join with the edges of lips in 85 continuous outline, and the two handles E E, each composed of two rings joined one below the other and projecting from the vase or main body directly under the curves of the lips.

In testimony whereof I have hereunto set 90 my hand in the presence of two witnesses.

HENRY J. SMITH.

Witnesses:

JOHN FREDERICK,
O. R. TAUDTE.
